DEODORANT HOLDER

Henry J. Brownstein, Chicago, Ill., assignor to Hysan Products Co., Chicago, Ill., a corporation of Illinois

Filed Apr. 25, 1961, Ser. No. 64,894

Term of patent 14 years

(Cl. D4—3)

FIG. 1 is a perspective view of a deodorant holder showing my new design, the fragmentary toilet bowl shown in broken lines being for illustrative purposes only;

FIG. 2 is a front elevational view thereof;

FIG. 3 is a rear elevational view thereof;

FIG. 4 is a side elevational view thereof the opposite side being substantially the same; and

FIG. 5 is a top plan view thereof shown in a non-operating position.

I claim:

The ornamental design for a deodorant holder, as shown and described.
